A. D. FRYE, JR., OF NEW YORK, N. Y.

Letters Patent No. 65,204, dated May 28, 1867.

IMPROVED BOUQUET-HOLDER.

The Schedule referred to in these Letters Patent and making part of the same.

TO ALL WHOM IT MAY CONCERN:

Be it known that I, A. D. FRYE, of the city, county, and State of New York, have invented a new and useful improvement in Bouquet-Stand and Handkerchief-Holder; and I do hereby declare that the following is a full, clear, and exact description thereof, which will enable others skilled in the art to make and use the same, reference being had to the accompanying drawings, forming part of this specification.

This invention relates to a new and improved method of forming and arranging bouquets of flowers, and to the new uses to which it may be applied; and it consists in providing a hollow tube, of any kind of metal or metals, around which the flowers forming the bouquet are arranged, and adapting it to other uses than a handle or stand for the bouquet, as will be hereinafter more fully described.

Figure 1 represents the flowers of a bouquet arranged around the tube according to my design. The tube in this figure is represented as a holder, and the flowers exposed or unmasked, the handkerchief being represented in the upper end of the holder.

Figure 2 represents the tube or holder as a stand, it being a vertical section of fig. 1, and presenting two separate views, one with the handkerchief inserted in the top of the holder, as in fig. 1, and another with the handkerchief spread over the bouquet, or representing it as masked; at the same time the scroll, which is seen in fig. 1 at the top of the bouquet, is placed at the bottom of the holder, forming a stand.

Figures 3, 4, and 5 represent detached views of the tube and scroll, showing modifications of the same, and the manner in which they are constructed.

Figure 6 represents a simple handle, which may be inserted in the bottom end of the tube, and used in certain cases.

Similar letters of reference indicate like parts.

A represents the tube. B, the scroll, which is used in either end of the tube. C is the handkerchief. D is a ribbon, which is tied around the tube over the stems of the flowers, as represented in the drawing. E is a ribbon or cord, which is attached to the centre of the handkerchief, and which hangs down through the tube with a ring attached for the finger, by which it may be held as represented. F is the handle, represented in fig. 6, and which may be made of pearl, ivory, or any other desired material. The tube A and the scroll B may be formed of any size or shape, and may be made of any suitable material, and in any desired style to suit the fancy.

As represented in fig. 1, a lady is holding the bouquet, with her handkerchief in the scroll in the centre. By shaking the bouquet slightly when in this position, the handkerchief leaves the scroll, and gently spreads itself out over the flowers, as represented in fig. 2. This covers or masks the bouquet. To unmask it, it is only necessary to draw down the ribbon E, and the flowers are exposed in a moment's time. When it is desired that the bouquet shall stand in a window, or in any other position, the scroll B is slipped from the top of the tube, and placed in the bottom end, as seen in fig. 2. When held in the hand, as represented in fig. 1, the scroll takes the place of a central flower. When the scroll B is to be withdrawn from the top of the bouquet, when it is unmasked, it is necessary to turn up the ribbon E, and to hold it with the thumb or finger, when the scroll can be drawn over the handkerchief without disturbing the flowers. a is a small hook attached to the tube beneath the flowers, from which the ribbon E may be suspended by the ring when the bouquet is standing. By this arrangement the bouquet is much easier made, as the stems of the flowers are tied around the tube, while the ends of the stems are screened from view by a tastefully tied ribbon. The lady is relieved of the trouble of holding her handkerchief in her hand, while the handkerchief is being perfumed by natural flowers. The tube also forms a safe and convenient receptacle for the lady's gloves at all times.

The bouquet has hitherto been prized mainly for its beauty. As I form it, it is rendered useful as well as more beautiful. There is another feature which renders the bouquet, when formed in this manner, additionally valuable, and which will be readily appreciated by those at a distance, who often receive these beautiful mementoes of love and affection, which have been torn and disarranged (unavoidably) in the course of transportation. By my arrangement a bouquet formed of the most delicate flowers may be secured and protected by the tube in a box, and transported, by express or otherwise, with perfect safety.

Having thus described my invention, what I claim as new, and desire to secure by Letters Patent, is—

The tube A, formed in one or more parts, in combination with the reversible scroll B, either removably, or securely attached, for the purpose of holding bouquets and handkerchiefs, substantially as herein shown and described.

The above specification of my invention signed by me this 6th day of March, 1867.
